UNITED STATES PATENT OFFICE.

WALTER W. HUNZICKER, OF MANSFIELD, OHIO, ASSIGNOR TO THE OHIO BRASS COMPANY, OF MANSFIELD, OHIO, A CORPORATION OF NEW JERSEY.

REELING DEVICE.

1,366,184.

Specification of Letters Patent. Patented Jan. 18, 1921.

Application filed April 10, 1919. Serial No. 289,084.

To all whom it may concern:

Be it known that I, WALTER W. HUNZICKER, a citizen of the United States of America, residing at Mansfield, in the county 5 of Richland and State of Ohio, have invented certain new and useful Improvements in Reeling Devices, of which the following is a specification.

This invention relates to improvements in 10 reeling devices and has more particular reference to the reeling and resetting mechanism. It is particularly adapted to use in controlling trolley poles and in my specifications I have so described its application and 15 operation although my invention has other applications.

One object of my invention is to provide an improved device of this character which will be simple, durable, reliable and compact in construction, and effective and efficient in operation.

Another object is to provide a trolley retriever embodying mechanism controlled by the tension of the retrieving spring for automatically setting the locking means when 25 restoring the device to normal operating condition.

A further object is to provide a device of 30 this character comprising means whereby it may be adjusted to obtain any desired amount of retrieving action.

Other objects of the invention will appear more fully hereinafter.

The invention consists substantially in the 35 construction, combination, location and arrangement of parts, all of which will be more fully hereinafter set forth, and claimed, and illustrated in the accompanying drawings, in which:

40 Figure 1 is a side view of a reeling device embodying my improvements and shown partly in section to illustrate the constructional arrangement of the various parts.

Fig. 2 is a sectional view taken on the line 45 2-2 of Fig. 1, and showing the parts in normal operative condition.

Fig. 3 is a sectional view substantially on the line 3-3 of Fig. 1, and showing the mechanism in normal condition, the retriever 50 disk being held in interlocked relation with the case.

Fig. 4 is a similar view indicating the mechanism in the act of unlocking the retriever disk and also showing the retriever disk unlocked from the case and about to commence its retrieving action.

Fig. 5 is a view of a portion of the opposite side of the retriever disk.

Figs. 6, 7 and 8 are views showing the locking mechanism and the operating means 60 in various positions and which will be referred to hereinafter.

The same reference characters indicate the same parts throughout the various views.

Referring to the drawings and which illustrate the embodiment of the preferred form of my invention, I provide a casing 1 provided with a cover 2, which may be removably secured thereto in any well known or suitable manner. The casing is formed with 65 a recess wherein is mounted a power or retracting spring 3, which has its outer end connected to the stud 4, of an actuated member 5, provided with a pin 6, to be referred to hereinafter. The upper end of this member 5 is slidably mounted between lugs 7, formed on the casing, while its lower or reduced end 8 extends within a cavity 9 formed in a projection provided on the casing. Mounted within this cavity is a compression 80 spring 10, one end of which bears against the casing at 11, while its other end operates against one side of a nut 12 having threaded engagement with the member 5. When the device is in operative condition the member 85 5 is held in the position shown in Fig. 2, the tension on the spring 10 being balanced by the tension of the power spring 3 when it is wound up. In this position of the member 5, it will be noted that its shoulder 13 is 90 held in spaced relation to the shoulder 14 of the casing, the shoulder 14 being adapted to coöperate with the shoulder 13 to limit the movement of said member 5 by the spring 10 when the tension of the power spring 95 weakens by reason of the spring 3 unwinding when the retriever parts retrieve.

The inner end of the power spring is connected, in any well known or suitable manner, to the hub 15 of the retriever disk or retrieving member 16, mounted to rotate in either direction upon the shaft 17. This 100

disk is adapted to be rotated in one direction by the power spring 3, to wind up the trolley rope and thereby pull down the trolley pole, and it is adapted to be rotated in the opposite direction for the purpose of re-winding the power spring to place said spring in wound condition. The retriever disk has a peripheral flange or rim 18 provided with a slot 19 in which is arranged a double latch which is adapted to normally lock the retriever disk to the casing so as to prevent its rotation and to hold the power spring under tension. This latch comprises two levers 20 and 21, which are pivoted at 22 and 23 respectively. Their inner or adjacent ends are pivotally connected together so that they will both be moved simultaneously. The lever 20 is notched at this end while the corresponding end of the lever 21 is formed and adapted to operate in said notch so that the two levers which constitute the latch form substantially a knuckle jointed device, as shown in Figs. 3 and 4. When the latch is in locking position, the free ends 24 and 25 respectively will be projected or thrown outward beyond the flange on the retriever disk and in position to engage the fixed lugs 26 and 27 which are formed integrally on the inner wall of the casing. For convenience of description I will hereinafter refer to the end 24 of the latch as the "lock" end, and the end 25 as the "stop" end. Thus it will be seen that when the latch is thrown out and the "lock" end 24 engages the "stop" lug 26 the retriever disk will be positively locked against rotation in a direction to wind up the trolley rope. The operation of the "stop" end of the latch will be described hereinafter. The two levers 20 and 21 which comprise this latch, are curved to coincide with the curvature of the flange 18, so that when said levers are in released position, as shown in Figs. 6 and 7, no portion of them will project beyond the periphery of the retriever disk, thus leaving the disk free to rotate. For the purpose of maintaining the latch in either position I provide a spring 28, (see Fig. 5). This spring has its inner end secured to the disk at 29 while its outer end is connected to the free end of one of the levers as shown, the relation of the parts being such that when the latch is actuated it will be moved completely to one or the other of its two positions, as the case may be, and held thereby by the spring 28.

Rotatably mounted, preferably upon another hub extension 30 of the retriever disk, is a drum 31 adapted to receive the trolley rope 32. This drum is formed with a compartment 33 wherein is mounted a service spring 34, which operates to rotate the drum in the direction to keep the trolley rope taut. The outer end of this spring is connected to the drum in any suitable or desirable manner while its inner end is connected to a

ratchet sleeve 35, which is mounted for adjustment by means of ratchet teeth between the sleeve 35 and the fixed shaft 17.

The drum, being connected to the rope secured to the trolley pole, normally follows the movement of the trolley pole and in case of an abnormally rapid rise in said pole, mechanism is actuated which will unlock the retriever disk and connect it to the drum so that the drum will be rotated in the direction to wind up the trolley rope and pull down the pole. In order to throw in the latch 24 and 25 and release the retriever disk the drum carries a plurality of centrifugal dogs 36 which are pivotally mounted in suitable sockets or bearings 37 formed in integral bosses 38 on the side of the drum adjacent the retriever disk. When normally operating, these dogs are yieldably maintained in inward or retracted position by springs 39, the free ends of the dogs resting against the adjacent bosses as shown in Fig. 3. These dogs are arranged so that they will be sensitive to abnormally rapid fluctuations of the trolley pole, such for instance as when the pole leaves the wire and flies upwardly. Because of the undue speed of the drum incident to the quick upward movement of the pole the dogs will move outwardly against the peripheral flange 18 on the retriever disk under the action of centrifugal force.

It will be noticed that the knuckle joint of the latch, when the latch is in locking position, lies within the flange 18 and hence within the path of the free ends of the tripping or centrifugal dogs 36. In consequence, the tripping dog, which at the instant is the nearest to the knuckle joint of the latch, will strike said joint and force it outwardly, thus throwing the "lock" and "stop" ends of the latch inwardly and release the retriever disk. In order to insure a positive releasing action on the part of the dogs, I provide an outstanding rib 40 on the face of the retriever disk adjacent the centrifugal dogs. This rib is positioned adjacent the knuckle joint of the latch to provide a comparatively narrow space between the rib and the flange 18. In addition the free ends of the tripping dogs are provided with extensions 41 of sufficient thickness to pass through the channel or space between the rib and flange and thereby positively force the knuckle joint of the latch outwardly. Assuming now that the latch 20 has been disengaged from the stop 26 and the retriever disk thus released, it now remains to lock the retriever disk and drum together so that the retriever disk will rotate the drum in the direction to wind up the trolley rope and pull down the pole. This is accomplished by the centrifugal tripping dog 36 which, after actuating the knuckle joint, passes said latch and continues until it reaches the shoulder 42 formed in the flange 18 of the retriever disk. By

thus engaging said shoulder the tripping dog positively interlocks the retriever disk and drum and the latter will thereby be carried with the retriever disk and will wind up the trolley rope.

In accordance with my invention I provide a guide rib 43 on the side of the retriever disk adjacent the member 5, and provide the lock end of the latch 20 with a lateral projection 44 adapted, when the latch is in released position, to assume a position in proximity to the end 45 of the rib as shown in Figs. 6 and 7, and the purpose of which will be described hereinafter.

In order that a clear understanding of my invention may be had, a brief statement of the operation is as follows. When the power spring is wound up or set and the parts are in their normal position they will be as represented in Figs. 1, 2, 3 and 5. The latch will be in outward position and the "lock" end 24 of the lever 20 held in engagement with the "lock" lug 26 of the casing. The member 5 will be held in the balanced position shown in Fig. 2 in which the compression of the spring 10 is balanced by the tension of the power spring 3. In this position of the member 5, its pin 6 is disposed below the end 45 of the guide rib 43 as shown in Fig. 3. The centrifugal dogs 36 will be held in engagement with the bosses 38 and the drum will be under the action of the service spring 34 and free to rotate in either direction and the trolley rope may be wound or unwound thereon. When the rope is rapidly unwound from the drum as when the trolley pole jumps the wire, the sudden impulse or rapid rotation of the drum will cause the dogs 36 to move outwardly by centrifugal force and actuate the latch and release the retrieving disk and finally interlock the drum with the disk in the manner described. (See Fig. 4.) When this has taken place the parts will be in the position shown in Fig. 4. After the latch 20-21 has been tripped by the centrifugal dog 36 the end 44 of latch 20 will assume the position shown in Fig. 6 with respect to the rib 43. Next the retriever disk and the drum will be caused to rotate in the rope winding direction and wind up the rope by the action of the power spring 3, thereby pulling down the trolley pole. As the drum rotates in a rope-winding or counter-clockwise direction, the power spring, which normally holds the actuating member 5 in extended position, weakens, whereupon the compression spring 10 will impart movement to the member 5 in the direction to cause its shoulder 13 to engage the shoulder 14 of the case. In this position of the member 5, its pin 6 will be positioned as shown in solid lines, Fig. 6, and in which position it is completely out of the path of the guide rib 43. Assuming now that the trolley rope has been wound up and the trolley pole

pulled down, it now remains to reset the device to normal operative condition. In order to accomplish this it is only necessary to pull out on the trolley rope, thereby unwinding the rope from the drum and turning the drum and the retriever disk in the direction indicated by arrow in Figs. 6, 7 and 8. As the rope is pulled out and the drum and retriever disk revolves, the power spring will be wound up until its tension becomes equal to or balances the pressure exerted upon the actuating member 5 by the compression spring 10. Then upon continued rotation of the parts in the same direction and the consequent further tensioning of the power spring the member 5, by reason of its connection with said spring, will be caused to move against the action of the spring 10, until its pin 6 will be in the position indicated by broken lines, Fig. 6. It will be apparent that when the member 5 is in this position by continued rotation of the disk movement will be imparted to the member 5 by reason of its pin 6 riding over the guide rib 43 and that the extension 44 of the lever 20 will be brought into engagement with the pin 6 and forced to move outwardly (see Figs. 7 and 8), and thus throw the latch into locking position. The guide rib 43 has an upward pitch; that is, its approach or forward end A is located considerably closer to the axis of the disk than its opposite end B, and when coöperating with the pin 6, causes the member 5 to move in the direction to further compress the spring 10 to such an extent that, after the pin passes over the rib, the increased compression will cause the member 5 to move to a position where its pin 6 will be out of the path of the end B of the rib. The operator continues pulling out on the rope until the stop end 25 (Fig. 8) of the latch strikes the stop lug 27 on the casing whereby further winding up of the spring or unwinding of the rope will be positively prevented and in which condition or relation of the parts the pin 6 will be out of engagement with the guide rib 43 as in Fig. 3. As soon, then, as the pull on the trolley rope is relaxed the disk will move in the reverse direction until the lock end 24 of the latch is brought into engagement with the lock stop 26 of the casing and locks the disk against rotation until it is again released by the centrifugal dogs. Fig. 3 shows the relation of the parts when the device is in normal operative condition.

From the foregoing it will be apparent that the mechanism which operates to automatically restore the latch to locking position is governed by the tension of the compression spring 10, and that by varying the tension of this spring, the device may be adjusted to obtain any desired amount of retrieving action within its limits of operation.

It now remains to release the drum from the retriever disk, which has been held interlocked while the parts were being restored to normal operative condition. This is accomplished as soon as the pull on the trolley rope is relaxed whereupon the drum will start to rotate in the opposite direction under the influence of the service spring 34, and in this movement it carries the centrifugal dog out of engagement with the stop shoulder 42 of the disk. This dog moves out until it passes the end of the ridge 46 and it is then drawn inwardly against the boss 38 by its spring 39, thus finally unlocking the drum from the disk and leaving the drum free to again normally wind up and unwind the trolley rope.

The amount of retrieving action is adjusted by altering the compression of the spring 10 by means of the adjusting nut 12. When the compression of the spring 10 is increased, the tension in the spring 3 required to overcome the compression of spring 10 is increased and this increased compression is secured by revolving the retrieving disk and reel, interlocked, a greater number of turns or part turn thereof, and the converse is true when the tension on the spring 10 is decreased.

Having thus fully described my invention, and illustrated one embodiment of the same, I do not wish to be limited to the details of the construction shown since these can obviously be changed without departing from the spirit and scope of the invention.

I claim:

1. In a reeling device the combination of a case, a normally stationary retrieving member therein, a power spring having engagement at one end with the member for rotating said retrieving member in one direction and connecting means between the other end of the spring and case, said means comprising an element movable relatively to the case and controlled by tension of the spring.

2. In a reeling device the combination of a case, a normally stationary rotatable member therein, a lock operable when set to hold the member against rotation by the spring, means for releasing the lock, a power spring constantly urging the member in one direction of rotation, means for rotating the member in the other direction to wind up the spring, said spring having engagement at one end with the member, and means between the other end of the spring and case for securing the spring to the case and for controlling the setting of the lock, said connecting and controlling means comprising an element connected to the spring and case and arranged for movement relatively to the case.

3. In a reeling device the combination of a case, a retrieving member therein, a spring for rotating the retrieving member in one direction, a lock for normally holding the member against rotation by the spring, a device for releasing the lock, means for rotating the retrieving member in the opposite direction and against the action of the spring to wind up the spring and means interposed between the spring and case for actuating the lock, said means comprising an element secured to the spring and having a yieldable connection with the case.

4. In a reeling device the combination of a case, a retrieving member therein, a spring constantly urging the retrieving member in one direction of rotation, a lock operable when set to hold the retrieving member against rotation by the spring, stops co-operating with the lock when set to hold the member against rotation, means for releasing the lock to permit rotation of the member by the spring, and means securing the spring to the case and actuated by the spring when wound up to a predetermined tension for setting the lock.

5. In a reeling device the combination of a case provided with a stop, a retrieving member therein, a spring constantly urging the member in one direction of rotation, a lock associated with the member to co-operate with said stop when set for normally holding the disk against rotation by the spring, an automatically operating device for releasing the lock to permit rotation of the member by the spring, means for rotating the disk against action of the spring to wind up the spring, and a device securing one end of the spring to the case and controlled by action of the spring when wound up to a predetermined tension for actuating the lock into position to engage said stop.

6. In a reeling device the combination of a case, a retrieving member therein, a spring tending to rotate the retrieving member in one direction, means for rotating the retrieving member in the other direction and against the tension of said spring, means for locking said retrieving member against rotation in the direction urged by said spring and means controlled by the tension of said spring for actuating the locking means, said means comprising an element connected to the spring and having a yieldable adjustable connection with the case whereby it may move relatively thereto.

7. In a winding device, a retrieving member, a support member, a spring for rotating the retrieving member in one direction, a lock operable when set to normally hold the retrieving member in interlocked relation with the support against rotation by the spring, and means interposed between

one end of the spring and the support member for controlling the setting of the lock through the tension of the spring for the purpose described.

5 8. In a reeling device the combination of a case, a rotatable member therein normally held in interlocked relation with the case against relative rotation, a lock operable when set to hold the member, means for releasing the lock, a power spring constantly tending to urge the member in one direction of rotation and having engagement at one end with the member, and connecting means between the case and the other end of the 10 spring for securing the spring to the case, said connecting means comprising an element secured to the other end of the spring and having a flexible connection with the case whereby it may move relatively 15 through a limited space.

9. The combination of a casing, a rotatable retrieving member having a rib, a lock carried by the member, spaced stops in the casing adjacent the periphery of the retrieving 20 member engageable by and between which the lock is normally positioned to hold the retrieving member against rotation in either direction, means for releasing the lock, a spring engaging the retrieving member and normally held under tension for rotating the member upon release of the lock, means for rotating the retrieving member in the direction against action of the 25 spring to wind up the spring, and means securing the spring to the casing and operable by action of the spring after the latter has been wound up to a predetermined tension 30 into position to be engaged by said rib during rotation of the member for actuating 35 the lock into normal position.

10. The combination of a casing, a retrieving member mounted therein, a spring constantly urging the retrieving member in one direction of rotation, means for rotating the retrieving member in the other direction, a latch carried by the retrieving member, an actuating member connected to the spring and movable thereby when said spring is wound to a predetermined tension 40 into position to be engaged by the retrieving member and moved into engagement with the latch to shift the latch into locking position, and spaced stop lugs on the casing between which the latch is positioned and 45 which are engaged by said latch to lock the retrieving member against rotation in either direction.

11. The combination of a casing, a rotatable retrieving member therein, a spring 50 constantly urging the retrieving member in one direction of rotation, means for rotating the retrieving member in the other direction to wind up the spring, a latch for locking the retrieving member against rotation

55 by the spring, coöperating means for the latch, means for releasing the latch, and mechanism secured to the spring and the casing and dependent upon the winding up of the spring to a predetermined tension for actuating said latch to lock the retrieving 60 member against rotation by the spring, said mechanism comprising a control spring, and means for adjusting the control spring to vary said predetermined tension.

12. In a reeling device the combination 75 of a case, a retrieving member therein, a spring for rotating the retrieving member in one direction, means for rotating the retrieving member in the other direction to wind up the spring, a latch operable when 80 set for normally locking the retrieving member against rotation by the spring, and means connecting the spring and the case and under the control of the spring for setting the latch when the spring has been 85 wound up to a predetermined tension.

13. The combination of a case having 90 guide lugs spaced apart, a rotary retrieving member therein, a spring constantly urging the retrieving member in one direction of 95 rotation, means for rotating the retrieving member in the reverse direction and against the tension of the spring to wind up the spring, a locking device carried by the retrieving member operable when set for locking the retrieving member against rotation in either direction, and mechanism under 100 the control of said spring and operable upon a predetermined tensioning of said spring for setting the lock, said mechanism embodying an element movably connected to the case and slidably arranged between 105 said guide lugs and having one end of the spring secured thereto.

14. In a reeling device the combination of 110 a case, a retrieving member therein, a spring constantly urging the member in one direction of rotation, a lock operable when set normally to hold the retrieving member against rotation by the spring, coöperating means for the lock, centrifugally controlled means for releasing the lock to permit rotation of the member by the spring, a movable device securing one end of the spring to the case and under the control of the spring 115 for setting the lock, and a second spring engaging the device and case and operating to resist movement of said device to actuate the lock prior to the winding up of the spring to a predetermined tension.

15. In a reeling device the combination of 120 a case, a retrieving member rotatably mounted therein and having a rib, a spring constantly urging the member in one direction of rotation, means for rotating the member 125 in the reverse direction to wind up the spring, a lock operable when set to hold the member against rotation by the spring,

means for releasing the lock, a device securing the spring to the case and actuated by the spring when wound up to a predetermined tension, a stud on the device to be 5 engaged by the rib and actuated into cooperating engagement with the lock for setting the lock during rotation of the member to wind up the spring after the device has

been actuated by the spring, and an adjustable yieldable connection between the device and spring for varying said predetermined tension. 10

In testimony whereof I affix my signature.

W. W. HUNZICKER.
